Application June 12, 1953, Serial No. 361,130

5 Claims. (Cl. 18—8)

This invention relates to spinnerets and more specifically to the novel orifices formed therein.

Revolutionary new methods for spinning synthetic textile filaments have recently been discovered which involve interfacial polymerization. In accordance with these methods filament formation and polymer formation are accomplished simultaneously when one of a pair of fast-reacting condensation polymer-forming intermediates is extruded as a shaped stream into a bath containing the complementary intermediate. Reaction then takes place between the intermediates at the interface between bath and stream to form a filamentary polymer in situ. Difficulty has been experienced in attempting to maintain continuous operation when using conventional spinnerets, which has been traced, at least in part, to jetting of the filamentary streams because of the low viscosity of the solutions. Viscose-type spinnerets, which have been used very successfully for years in the coagulation spinning of cellulose xanthate solution, which is of relatively great viscosity, do not give satisfactory results in this new interfacial polymerization-spinning process.

It is therefore an object of this invention to provide a satisfactory spinneret for use in interfacial polymerization-spinning. Another object of this invention is to provide a novel spinneret. Other objects will become apparent from the description that follows and the claims.

The objects of this invention are accomplished by preparing a viscose-type spinneret in the usual way and then subjecting the face thereof to a special polishing treatment whereby the shoulders of the orifices are rounded and the areas around the orifices are slightly recessed, as described in detail hereinafter. Spinnerets prepared in this way are satisfactorily adapted for use in interfacial polymerization-spinning, and continuous spinning of good, uniform multifilament yarn over long periods of time becomes possible through the use of these novel spinnerets.

In the drawings, which illustrate a preferred embodiment of the invention,

Figure 1 is a plan view drawn from a microinterferometer photograph of a single hole of a spinneret prepared in accordance with this invention (about 200 diameters enlargement),

Figure 2 is a sectional elevation corresponding to Figure 1, and

Figure 3 is a normal size view of a typical spinneret. Spinnerets of the prior art have been made of a variety of materials including noble metal alloys, such as platinum and gold or platinum and rhodium, base metal alloys, such as stainless steel, and non-metallic materials, such as glass or plastic. Any of these may be used in accordance with the present invention, but tantalum has been found preferable in spinnerets for use in interfacial polymerization-spinning. A tantalum spinneret such as one of the forms common to the viscose art, is mounted in a conventional viscose-type spinneret polisher which turns the spinneret during polishing so that it is polished in all directions parallel to the face. The spinneret sur-

2

face is shaped by polishing for a sufficiently long time with chrome rouge (Grade T-91 manufactured by S. A. Day Manufacturing Company is suitable), used with a light mineral oil on a felt wheel. Preferably this treatment is followed by polishing with a dispersion of aluminum oxide grain powder, such as grit No. 1000-W, in monopole oil and water on a jeweler's cloth wheel to remove scratches and put a finer polish on the spinneret surfaces.

10 The treatment with the coarser abrasive is continued for sufficient time to round off the orifice shoulders as shown in Figures 1 and 2 to a depth of at least 0.05 times the orifice diameter. The area around an orifice of a suitably processed spinneret appeared as shown in Figure 1 when photographed with a microinterferometer at a magnification of 200 diameters. The generally circular lines surrounding the orifice are the contour lines projected on the surface with this instrument, and each successive line indicates a difference in depth of 10 millionths of an inch. The orifice diameter was 0.003 inch, and the diameter of the depressed area within the outermost, generally circular, contour line 10 was about 0.014 inch. The spacing of the contour lines indicates that the slope of the depressed area, which was gradual near the outside, became increasingly steep and reached a depth of about 0.0004 inch at the edge 12 of the orifice.

Figure 2 was drawn from Figure 1 by projecting points of intersection of the contour lines with a diameter. Only one-tenth the number of contour lines shown in Figure 1 can be shown in Figure 2, because of crowding of the lines, so the distance between the lines represents 0.0001 inch on the actual spinneret. The shape of the depressed area shown is typical of suitable spinnerets prepared in accordance with this invention. The shoulders of the orifice have been polished to an approximately parabolic curvature. The precise amount of dishing or cupping of the spinneret face may be varied as required and will depend upon the diameter of the orifice, the particular use for which intended, and the spacing of orifices in a multiple hole spinneret, such as that shown in Figure 3. Spinnerets, depending upon the use, may have any number of orifices from 1 to 10, 20, 50 or 100 or more.

For interfacial polymerization-spinning, spinnerets should have the orifice shoulders rounded to a maximum depth at the orifice edge 12 of about 0.07 to 0.2 times the diameter of the orifice, the maximum diameter of the depression within the more or less circular boundary 10 should be about 3 to 6 times the diameter of the orifice, and the shape of the depression should approximate the shape shown in Figure 2. This shape may be expressed mathematically by the parabolic equation $y^2 = kx$, where x is the horizontal distance from the edge of the orifice of a point on the curved surface, y is the elevation of the point above the maximum depth of the depression at 12, and k is a constant whose value is readily determined by substituting values of x and y , e.g., for the spinneret illustrated k is about 0.00003. Within these general specifications the precise dimensions for optimum conditions will depend upon the material extruded, the desired rate of spinning and the spinneret material.

Other methods for producing the depressed areas around the orifices in the spinneret face may be used provided the method produces the desired rounded orifice shoulders as described herein. Variations include the conventional grinding, polishing or buffing techniques of the art, but employing suitable abrasives and/or continuing the treatment for an unusually long time to produce the required result with the particular spinneret material.

Since many different embodiments of the invention

may be made without departing from the spirit and scope thereof, it is to be understood that the invention is not limited by the specific illustrations except to the extent defined in the following claims.

What is claimed is:

1. In a spinneret assembly for spinning textile filaments the improvement comprising in combination a spinneret having orifice shoulders at the face of the spinneret rounded to an approximately parabolic curvature extending to a depth at the edge of the orifice of from about 0.05 to about 0.2 times the orifice diameter.

2. In a spinneret assembly for spinning textile filaments the improvement comprising in combination a spinneret having orifice shoulders at the face of the spinneret rounded to a depth at the edge of the orifice of from about 0.07 to about 0.2 times the diameter of the orifice.

3. In a spinneret assembly for spinning textile filaments the improvement comprising in combination a spinneret having orifice shoulders rounded to an approximately parabolic curvature reaching a depth at the edge of the orifice of from about 0.07 to 0.2 times the diameter of the orifice.

4. In a spinneret assembly for spinning textile filaments the improvement comprising in combination a spinneret having an orifice surrounded by a recessed area at the face of the spinneret of about 3 to 6 times the diameter of the orifice and sloping to a depth at the edge of the orifice of from about 0.07 to 0.2 times the diameter of the orifice.

5. In a spinneret assembly for spinning textile filaments

the improvement comprising in combination a spinneret having orifice shoulders at the face of the spinneret rounded to approximate a parabolic curvature of the form $y^2 = kx$ where x is the perpendicular distance from the

5 edge of the orifice of a point on the curved surface, y is the elevation of the point above the maximum depth of the curve at the orifice edge and has a value of from about 0.07 to 0.2 times the diameter of the orifice, k is a constant, and the diameter of the curved surface is from 10 about 3 to 6 times the diameter of the orifice.
